FLOODLIGHT

John C. Pritchett, Montreal, Quebec, Canada, assignor to Crouse-Hinds Company, Syracuse, N.Y., a corporation of New York

Filed Mar. 3, 1965, Ser. No. 84,059

Term of patent 14 years

(Cl. D48—20)

The side of the floodlight opposite to that shown in FIGURE 3 is identical with that shown in said figure.

I claim:

The ornamental design for a floodlight, as shown and described.
